UNITED STATES PATENT OFFICE.

MELVIN J. FOYER, OF TOLEDO, OHIO, ASSIGNOR TO OUTING KUMFY-KAB COMPANY, OF LAPORTE, INDIANA, A CORPORATION OF INDIANA.

CHILD'S SULKY.

1,199,064.

Specification of Letters Patent. Patented Sept. 26, 1916.

Application filed September 7, 1911, Serial No. 648,094. Renewed December 13, 1915. Serial No. 66,655.

To all whom it may concern:

Be it known that I, MELVIN J. FOYER, a citizen of the United States, residing at Toledo, in the county of Lucas and State of Ohio, have invented certain new and useful Improvements in Children's Sulkies; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 My invention is concerned with collapsible, children's sulkies of the general type shown in the patent to Brown No. 1,074,349, dated September 30, 1913, but which is an improvement on that of the aforesaid Brown 20 patent mainly in that the draft tongue is connected by suitable means with the collapsible mechanism, so that the leverage of the folding tongue may be utilized to collapse the sulky, or to open it, as the case 25 may be.

My invention is also designed to furnish means for the adjustment of the draft tongue of a sulky, whereby the seat may remain level, regardless of the height of 30 the person operating the sulky.

My invention also relates to certain novel combinations and details of construction hereinafter described and particularly pointed out in the claims.

35 To illustrate my invention, I annex here-to four sheets of drawings, in which the same reference characters are used to designate identical parts in all the figures, of which—

40 Figure 1 is a perspective view of my device seen from the rear, with the wheels removed for the sake of clearness; Fig. 2 is a side elevation of the same, with a portion of the wheel next to the observer broken 45 away; Fig. 3 is a similar view, showing the sulky partly folded; Fig. 4 is a similar view, showing the sulky still further folded; Fig. 5 is a bottom, plan view of the sulky, with the parts collapsed; Fig. 6 is an enlarged side view of the locking mechanism 50 which secures the sulky in erected position and which provides for the adjustment of the tongue; Fig. 7 is a side view of the device which, taken in connection with the 55 latch illustrated in Fig. 6, secures the sulky

in collapsed position; and Fig. 8 is a front elevation of one of the wheel-frames, hereinafter referred to, detached.

The base of the sulky, *i. e.*, the part that is not moved in collapsing, is a horizontal main frame, made up of two parts rigidly secured together. The upper, transverse portion 1 is composed of front, rear and side members. Each side member of the frame has two downwardly projecting brackets 2, to which is pivoted, at each side of the frame, by the pins 6, a downwardly extending wheel-support or wheel-frame, carrying at its lower end an axle 4 for the supporting wheels 5. The above-described pivotal connections between the wheel-frames 3 and the main frame permit the frames 3, with their wheels, to be folded beneath the main frame with one of the wheels overlapping the other, as illustrated in Fig. 5. The upper ends of the wheel-frames 3 contact, when they are erected, with the side members of the frame 1, forming stops which limit the outward swing of the wheel-frames. The second, or longitudinal, portion of the main frame consists of a thin, metal bar 7, bent, as seen at 8, into two parallel portions, and is rigidly secured to the front and rear members of the transverse portion of the frame 1, as at 9, 85 and at its rear end extends slightly backwardly of the transverse portion of the frame, and at its forward end furnishes a support for the draft tongue 10, which is pivoted, as at 11, upon and between the two forward extremities of the bar 7, so that the tongue may be swung forwardly into operative position or backwardly onto the vehicle between the two ends of the bar 7.

12 is a front standard, consisting of a thin bar of metal, bent at its middle to form two parallel portions which are respectively pivotally connected, as at 13, to the longitudinal portion 7 of the main frame. This standard is designed, primarily, to prevent the sulky from tipping forward and its lower end preferably has a loop 12^a formed therein, as best seen in Figs. 1 and 5, which may be used as a handle by which to carry the sulky when it is collapsed. Pivoted, as at 14, to the portion 7, near its rear end, is a rear support 15, consisting of a thin bar of metal, bent at its middle to form two parallel portions, the extremities of which are connected to the portion 7 by the pivots 110

14. This downwardly extending rear support 15 is designed to prevent the sulky from tipping over backward. Two bars 16, constituting a frame for the foot-rest 51 secured thereto, connect the front standard 12 and the rear support 15 by means of pivots 17 at their forward ends and pivots 18 at their rear ends. The upper ends of the front standard 12 are pivotally connected, as at 19, with the rear ends of the load bars 20, which, at their forward ends, are pivotally connected, as at 21, with the tongue 10, forward of the pivot 11. At the forward end of the portion 7 of the main frame is a latch 22, slidable in a housing 23 secured to the forward end of the portion 7 and pressed outwardly by a spring 24 (see Fig. 6). The latch 22 has at its rear end a ring 25, by which it may be retracted. Secured to the rear, or inner, end of the tongue 10 is a plate 26, bent at an angle, as shown, and provided with a series of holes 27 in the same vertical plane as that of the end of the latch 22. The latch being engaged with the middle hole 27, the tongue is held in alignment with the forward end of the main frame, as shown in Fig. 6. If the latch be engaged with the uppermost hole 27, the outer end of the tongue will, of course, be held elevated, and if the latch be engaged with the lowest hole 27, the outer end of the tongue will be depressed. Thus the handle of the tongue 10 may be accommodated to persons of different heights, varying from children to tall persons, without disturbing the horizontal position of the frame and seat.

Between the side members of the standard 12, at the forward end of the connecting bars 16, is rigidly secured a catch-piece 28, having a hole, or equivalent means, 29, adapted for engagement with the latch 22 (see Figs. 2, 3 and 7). The relation of the latch 22 and the catch-piece 28 is such that when the lower end of the standard 12 is swung forwardly, the catch-piece 28 describes an arc of a circle, of which the pivot 13 is the center. The inclined surface of the latch-piece 28 strikes the end of the spring-latch 22 which lies in its path, causing the latch to spring into engagement with the hole 29 in the catch-piece. It will now be seen that when the latch 22 is disengaged from the rear end of the tongue 10, the tongue may be swung backwardly upon the pivot 11 onto the top of the vehicle. This movement of the tongue forces backwardly the pivoted load bars 20, swinging the upper end of the standard 12 upon its pivot 13, thus bringing its lower end into substantially parallel relation with the tongue and forward portion of the main frame. The forward swing of the lower end of the standard 12 through the connecting rod 16 also causes the rear support

15 in like manner to swing forwardly and upwardly into substantially parallel relation with the main frame of the vehicle. At the end of this forward swing, the latch 22 springs into engagement with the catch-plate 28, as above described, locking the tongue and all parts connected with it in collapsed position.

30 is a wheel-frame erecting bail, consisting of a rod bent in U-shape and pivotally connected, near its ends, with the inner sides of the side members of the frame 1, as at 31. To the lower part of each of the wheel-frames 3 is rigidly secured forwardly pointing hooks 32 (see Figs. 1 and 8), which hooks, when the sulky is erected, engage the side arms of the bail 30 close to their lower ends. The bail, when in this position and engaged with the hooks on the wheel-frames, forms a brace which holds the wheels erected and prevents their swinging in either direction upon their pivots 6. Secured to the two members of the connecting bar 16 is a cross-bar 33, the upturned ends of which are provided with deep notches or slots 34 which engage the cross-member of the bail 30, and in which such cross-member has a limited, sliding movement. When the tongue of the sulky is swung backwardly, resulting in the forward swing of the standard 12 and rear support 15 and their connecting bars 16, as above described, the bail 30 is, by the slotted piece 33, pulled out of engagement with the hooks 32 and is swung forwardly and upwardly upon its pivots 31. Rigidly secured to the wheel-frames 3, and projecting inwardly in the path of the upright arms of the bail 30 are hooks 35 (see Figs. 3 and 8). As the bail swings forwardly and upwardly, its side members catch these hooks and swing the wheel-frames 3 inwardly upon their pivots 6 into horizontal position. One of the hooks 35 is a trifle lower on its wheel-frame than the other one, so that one of the wheel-frames is caught and swung in advance of the other and so that one of the wheels is caused to overlap the other without interference. At the end of the movement of the bail both wheels are pressed close against the bottom of the vehicle. When the tongue is thrown forward to erect the folding parts of the structure by the reversal of the movement above described, the parallel sides of the bail 30 are caused to rub against the inner sides of the wheel-frames and force them into extended position, while the bail is again engaged with the hooks 32. The vertical arms or sides of the bail 30 will be seen in their action to be a pair of depending levers, fulcrumed at 31 on the main frame and connected at their lower ends by a cross-bar to which power is applied to operate the levers.

The seat 36 is provided with a back 38, preferably supported by substantially ver-

tical bars 38^a, pivoted, as at 39, to the rear corners of the seat. The seat is also provided with side arms, or arm-rests 40, pivoted at their rear ends, as at 41, to the bars 38^a, and pivoted at their front ends, as at 42, to the upper ends of the bars 43, which, at their lower ends, are pivoted, as at 44, to the lateral edges of the seat, near its front. It will be seen that the parts numbered from 10 38^a to 44, inclusive, constitute a folding mechanism, which permits the side arms to be folded forwardly in parallel relation with the seat and to be unfolded into operative form. If the seat back 38 is secured to 15 the bars 38^a, as shown, it also will be folded with the side arms. This folding and unfolding operation is effected by means now to be described. The ends of the upright members or levers of the bail 30 project 20 above the pivots 31 and are pivotally connected, as at 45, to the front ends of the connecting bars 46, which, at their rear ends, are pivotally connected, as at 47, to the lower ends of a bail 48. This bail consists of a 25 rod, bent into U-shape and pivoted near the extremities of its parallel arms, as at 49, upon the rearwardly projecting ends of the side members of the frame 1. The horizontal cross-member of the bail 48 passes 30 through two elongated loops 50, secured to the bars 38^a and projecting backwardly from the same, this slidible connection being necessitated by the fact that the bars 38^a are pivoted to the spring supported seat instead 35 of to the main frame, as is the usual practice.

When the tongue of the sulky is swung backwardly, swinging the bail 30 forwardly through the connections and means hereinbefore described, the upper ends of the upright members of the bail 30 push the connecting bars 46 backwardly, pressing against the lower ends of the bail 48; thus tilting the upper part of the bail forwardly on its pivots 49 and swinging the seat back and 45 the side arms on their pivotal supports forwardly and down upon the seat 36. The lifting and swinging of the tongue forwardly causes a reversal of these movements and erects the seat-arms and the seat- 50 back into operative position. I have designated the bars 20 as "load" bars for the reason that the tongue 10, being a lever, its pivot is the fulcrum, and the bars 20 are the means by which the load of collapsing the 55 vehicle is applied to the tongue.

It will be observed that the connections between the tongue and the other parts are such that the seat-back is folded in advance of the folding of the wheels, and that the 60 wheels are unfolded in advance of the unfolding of the seat-back, so that the sulky needs to be lifted from the ground only during the folding and unfolding of the wheels.

When the sulky is in use, the occupant is 65 seated directly over the transverse portion

1 of the frame, with his feet astride of the extension 7 thereof and resting upon the foot-rest 51, consisting of a cross-bar secured to the foot-rest bars 16 in front of and below the seat. It will be obvious that these 70 bars 16 have a double function of forming a frame for the foot-rest and of operating connections between the front standard 12 and the rear support 15 and the operating bail 30.

While I have shown and described my invention as embodied in the form which I at present consider best adapted to carry out its purposes, it will be understood that it is capable of modifications and that I do not 80 desire to be limited in the interpretation of the following claims, except as may be necessitated by the state of the prior art.

What I claim as new and desire to secure by Letters Patent of the United States is: 85

1. In a collapsible sulky, the combination of a main frame, with a pair of wheel-frames pivoted beneath the sides so as to be parallel thereto, a front standard depending from the forward portion of the main frame, a draft tongue fulcrumed on the forward portion of the main frame, and operating connections between said tongue and said wheel-frames and standard, whereby said frames and standard are collapsed by 95 the power applied to the tongue as it is folded back over the frame and erected as it is swung forward to its draft position.

2. In a collapsible sulky, the combination of a main frame, with a pair of wheel-frames pivoted beneath the sides so as to be folded parallel thereto, a front standard depending from the forward portion of the main frame, a rear support extending to the rear of and beneath the main frame, a draft 100 tongue fulcrumed on the forward portion of the main frame, and operating connections between said tongue and said wheel-frames, standard and rear support, whereby said frames, standard and support are collapsed by 105 the power applied to the tongue as it is folded back over the frame and erected as it is swung forward to its draft position.

3. In a collapsible sulky, the combination 115 of a main frame, with a pair of wheel-frames pivoted beneath the sides so as to be folded parallel thereto, a rear support extending to the rear of and beneath the main frame, a draft tongue fulcrumed on the forward portion of the main frame, and operating connections between said tongue and said wheel-frames and support, whereby said frames and support are collapsed by 120 the power applied to the tongue as it is folded back over the main frame and erected as it is swung forward to its draft position.

4. In a collapsible sulky, the combination 125 of a main frame, with a pair of wheel-frames pivoted beneath the sides so as to be folded 130

- parallel thereto, a front standard depending from the forward portion of the main frame, a horizontal foot-rest frame connected to the front standard and movable toward and from the main frame, a draft tongue fulcrumed on the forward portion of the main frame, and operative connections between said tongue and said wheel-frames, standard and foot-rest frame, whereby said frames and standard are collapsed by the power applied to the tongue as it is folded back over the main frame and erected as it is swung forward to draft position.
5. In a collapsible sulky, the combination of a main frame, with a pair of wheel-frames pivoted beneath the sides so as to be folded parallel thereto, a front standard depending from the forward portion of the main frame, a rear support extending to the rear of and beneath the main frame, a horizontal foot-rest frame connected to the front standard and rear support and movable toward and from the main frame, a draft tongue fulcrumed on the forward portion of the main frame, and operating connections between said tongue and said wheel-frames, standard, rear support and foot-rest frame, whereby said frames, standard and support are collapsed by the power applied to the tongue as it is folded back over the main frame and erected as it is swung forward to its draft position.
6. In a collapsible sulky, the combination of a main frame, with a pair of wheel-frames pivoted beneath the sides so as to be folded parallel thereto, a front standard depending from the forward portion of the main frame, a rear support extending to the rear of and beneath the main frame, a horizontal foot-rest frame connected to the front standard and rear support and movable toward and from the main frame, a draft tongue fulcrumed on the forward portion of the main frame, and operating connections between said tongue and said wheel-frames, standard, rear support and foot-rest frame, whereby said frames, standard and support are collapsed by the power applied to the tongue as it is folded back over the main frame and erected as it is swung forward to its draft position, said connections including an operating bail pivotally connected to the main frame and co-operating with the wheel-frames to erect and collapse them.
7. In a collapsible sulky, the combination of a main frame, with a pair of wheel-frames pivoted beneath the sides so as to be folded parallel thereto, a front standard depending from the forward portion of the main frame, a horizontal foot-rest frame connected to the front standard and movable toward and from the main frame, a draft tongue fulcrumed on the forward portion of the main frame, and operative con-

nnections between said tongue and said wheel-frames, standard and foot-rest frame, whereby said frames and standard are collapsed by the power applied to the tongue as it is folded back over the main frame and erected as it is swung forward to draft position, said connections including an operating bail pivotally connected to the main frame and co-operating with the wheel-frames to erect and collapse them.

8. In a collapsible sulky, the combination of a main frame, with a pair of wheel-frames pivoted beneath the sides so as to be folded parallel thereto, a front standard pivoted to and depending from the forward portion of the main frame, a rear support pivoted to and extending to the rear of and beneath the main frame, a horizontal foot-rest frame connecting the front standard and the rear support, an operating bail, pivoted to the main frame, co-operating with the wheel-frames to erect and collapse them and operatively connected with the foot-rest frame, a draft tongue pivoted on the forward portion of the main frame, and a load bar connecting the tongue and the front standard, as and for the purpose described.

9. In a collapsible sulky, the combination with a main frame having a seat supported therefrom, of a pair of wheel-frames, each carrying a wheel pivoted thereto beneath the sides so as to be folded beneath the seat, means for preventing the sulky tipping unduly on the single pair of wheels, collapsible side frames extending above the main frame adjacent the seat, a draft tongue fulcrumed on the forward portion of the main frame, and operating connections between said tongue and said wheel-frames and side frames, whereby the wheel frames are collapsed inwardly and upwardly and the side frames forwardly and downwardly by the power applied to the tongue as it is folded back on the main frame and erected as the tongue is swung forward to its draft position.

10. In a collapsible sulky, the combination with a main frame having a seat supported therefrom, of a pair of wheel-frames, each carrying a wheel pivoted thereto beneath the sides so as to be folded beneath the seat, means for preventing the sulky tipping unduly on the single pair of wheels, collapsible side frames extending above the main frame adjacent the seat, each consisting of a pair of vertical arms pivoted at their lower ends and pivotally connected by a horizontal bar forming an arm rest, a draft tongue fulcrumed on the forward portion of the main frame, and operating connections between said tongue and said wheel-frames and side frames, whereby the wheel frames are collapsed inwardly and upwardly and the side frames forwardly and downwardly by the power

applied to the tongue as it is folded back on the main frame and erected as the tongue is swung forward to its draft position.

11. In a collapsible sulky, the combination with a main frame, of a seat, springs interposed between said frame and seat, a pair of wheel-frames, each carrying a wheel pivoted to the main frame beneath the sides thereof so as to be folded beneath the seat, means for preventing the sulky from tipping unduly on the single pair of wheels, collapsible side frames extending above the main frame adjacent the seat, a draft tongue fulcrumed on the forward portion of the main frame, and operating connections between said tongue and said wheel-frames and side frames, whereby the wheel-frames are collapsed inwardly and upwardly and the side frames forwardly and downwardly by the power applied to the tongue as it is folded back on the main frame and erected as the tongue is swung forward to its draft position.

12. In a collapsible sulky, the combination with a main frame, of a seat, springs interposed between said frame and seat, a pair of wheel-frames, each carrying a wheel pivoted to the main frame beneath the sides thereof so as to be folded beneath the seat, means for preventing the sulky from tipping unduly on the single pair of wheels, collapsible side frames extending above the main frame adjacent the seat, a draft tongue fulcrumed on the forward portion of the main frame, and operating connections between said tongue and said wheel-frames and side frames, whereby the wheel-frames are collapsed inwardly and upwardly and the side frames forwardly and downwardly by the power applied to the tongue as it is folded back on the main frame and erected as the tongue is swung forward to its draft position, said connections including a load bar pivoted at its outer end to the tongue and at its inner end to the collapsing mechanism.

13. In a collapsible sulky, the combination with a main frame having a seat supported therefrom, of a pair of wheel-frames, each carrying a wheel pivoted thereto beneath the sides so as to be folded beneath the seat, means for preventing the sulky tipping unduly on the single pair of wheels, collapsible side frames extending above the main frame adjacent the seat, a draft tongue fulcrumed on the forward portion of the main frame, and operating connections between said tongue and said wheel-frames and side frames, whereby the wheel frames are collapsed inwardly and upwardly and the side frames forwardly and downwardly by the power applied to the tongue as it is folded back on the main frame and erected as the tongue is swung forward to its draft position, said connec-

tions including an erecting bail pivoted to the main frame and coöperating with the wheel-frames, a load bar pivoted at one end to the tongue, and connections between the other end of the load arm and the erecting bail.

14. In a collapsible sulky, the combination with a main frame having a seat supported therefrom, of a pair of wheel-frames, each carrying a wheel pivoted thereto beneath the sides so as to be folded beneath the seat, a front standard depending from the forward end of the main frame, collapsible side frames extending above the main frame adjacent the seat, an erecting bail coöperating with the wheel frames, a draft tongue fulcrumed on the forward portion of the main frame, a load bar connecting the tongue and the front standard, and connections between said standard and the erecting bail and side frames, substantially as and for the purpose described.

15. In a collapsible sulky, the combination with a main frame having a seat thereon, of a pair of wheel-frames, each carrying a wheel pivoted thereto beneath the sides so as to be folded beneath the seat, an erecting bail pivotally connected to the main frame and coöperating with the wheel-frames, a front standard pivoted to the forward end of the main frame, a foot-rest frame pivotally connected to the front standard and the erecting bail, a draft tongue fulcrumed on the forward portion of the main frame, and a load bar connecting said tongue and the front standard, as and for the purpose described.

16. In a collapsible sulky, the combination with a main frame, of a seat located above the same, springs interposed between said main frame and the seat, a pair of wheel-frames each carrying a wheel pivoted thereto beneath the sides so as to be folded beneath the seat, means for preventing the sulky tipping unduly on the single pair of wheels, collapsible side frames pivoted to the seat and extending above the main frame, a draft tongue fulcrumed on the forward portion of the main frame, and operating connections between said tongue and said wheel-frames and side frames, whereby the wheel-frames are collapsed inwardly and upwardly and the side frames forwardly and downwardly by the power applied to the tongue as it is folded back on the main frame and erected as the tongue is swung forward to its draft position, said connections including slotted bars connected to the side frames, a seat-erecting bail pivoted to the main frame and extending through the slotted bars, an erecting bail pivoted on the main frame and coöperating with the wheel-frames, and a connecting link between the two bails.

17. In a child's sulky, the combination with a running gear, of a tongue secured thereto, and means for adjusting and locking the tongue to vary the angle at which it shall stand to the plane of the running gears. 70
18. In a collapsible sulky, the combination of a main frame, with a pair of wheel frames pivoted beneath the sides so as to be folded parallel thereto, a front standard depending from the forward portion of the main frame, and operating connections between the standard and the wheel frames whereby they will be collapsed and erected together, 75
19. In a collapsible sulky, the combination of a main frame, with a pair of wheel frames pivoted beneath the sides so as to be folded parallel thereto, a front standard depending from the forward portion of the main frame, a draft tongue fulcrumed on the forward portion of the main frame, and operating connections between said tongue and said wheel frames and standard whereby said frames and standard are collapsed by the power applied to the tongue as it is folded back over the main frame and erected as it is swung forward to its draft position, said standard having its end engaging the ground when erected shaped so that it can be used as a handle when the sulky is collapsed. 80
20. In a collapsible carriage, the combination of a frame, wheel supports mounted on said frame to collapse under the same, means for erecting and collapsing said wheel supports, comprising levers pivoted on said frame, a tongue pivoted to said frame, links connecting said levers to said tongue. 85
21. In a collapsible carriage, the combination of a frame, wheel supports mounted on said frame to collapse under the same, means for actuating said wheel supports comprising a lever mounted on said frame, a tongue pivoted on said frame, links connecting said lever to said tongue whereby the lever is actuated to erect and collapse the wheel supports when the tongue is extended and collapsed, and a foot rest, said foot rest having operative connections to 90
22. In a collapsible carriage, the combination of a frame, wheel supports mounted on said frame to collapse under the same, means for actuating said wheel supports comprising a tongue mounted on said frame to collapse rearwardly thereon, said tongue having operative connections with said wheel supports whereby they are erected 95
23. In a collapsible carriage, the combination of a frame, wheel supports mounted on said frame to collapse under the same, means for actuating said wheel supports comprising a tongue mounted on said frame to collapse rearwardly thereon, and a collapsible foot rest having operative connection with said tongue whereby the foot rest is collapsed and extended when the tongue is collapsed and extended. 100
24. In a collapsible carriage, the combination of a frame, a collapsible tongue, a collapsible foot rest, a standard, and operative connections for said foot rest and standard to said tongue whereby said foot rest and standard are swung to and from extended position as the tongue is swung to and from its extended position. 105
25. A child's sulky, comprising a main frame provided with a seat, a front standard and a rear support pivoted adjacent the opposite ends of said frame, links connecting said standard and support, a tongue pivoted to the forward end of the frame, wheel supports pivoted to said frame, a bail having its ends pivoted to the frame and having an operative connection with said links and forming in its operative position a brace for the wheel supports, a link connecting said front standard and the tongue, and means to lock the tongue in extended and folded positions. 110
26. A child's sulky, comprising a main frame provided with a seat, a front standard and a rear support pivoted adjacent the opposite ends of said frame, links connecting said front standard and rear support, a tongue pivoted to the forward end of the frame, wheel supports pivoted to said frame, a bail having its ends pivoted to the frame and having an operative connection with said links and forming in its operative position a brace for said wheel supports, a pivoted seat back, a second bail pivoted to the frame and slidingly connected to the seat back, means connecting said bails, a link connecting said front standard and the tongue, and means to lock the tongue in extended and folded position. 115
27. In a child's sulky, a main frame, a seat, a support pivoted to the frame for preventing the seat from tilting too far backwardly, a tongue pivoted to the forward end of the frame and adapted to be folded into substantially parallel relation with said seat when in folded position, and connections between the support and tongue whereby the movement of the tongue into and out of operative position imparts a like movement to the support. 120
- 125
- 130

28. In a child's sulky, a main frame carrying a seat, supports for preventing the seat from tilting too far forwardly or backwardly pivoted to the frame, a tongue pivoted at 5 the forward end of the frame and adapted to be folded into parallel relation with said seat when in folded position, and connections between the supports and tongue whereby the movement of the tongue into 10 and out of operative position imparts a like movement to the supports.

29. In a child's sulky, a main frame carrying a seat, a pair of foldable wheel supports, a support pivoted to said frame for 15 preventing the seat from tilting too far backwardly, a tongue pivoted to the forward end of said frame, and connections between said supports and the tongue for moving said supports into substantially 20 parallel relation with the seat by the movement of the tongue.

30. In a child's sulky, a pair of foldable interconnected wheel supports, a frame on which they are pivoted, a seat carried by 25 said frame, supports pivoted respectively at the rear and forward ends of said frame for preventing the seat from tilting too far backwardly or forwardly, a tongue pivoted to said frame, and connections between said 30 several supports and the tongue for moving said supports into substantially parallel relation with the seat by the movement of the tongue.

31. In a child's sulky, a main frame carrying the seat, a support which prevents the seat from tilting too far backwardly, interconnected wheel supports, a back for the seat, a tongue, and operative connections between the tongue and the several supports 40 and the seat back for causing said several connected members to move in harmony into and out of operative position.

32. In a child's sulky, a main frame carrying a seat, pivoted wheel supports, a pivoted bail for the wheel supports, a support to prevent the vehicle from tilting too far, a pivoted seat back, a second bail for said seat back having sliding engagement therewith, links connecting said bails, a tongue, 50 and operative connections between the tongue, the wheel supports and said bail for

the wheel supports for moving the seat back and said bail into substantially parallel relation with the seat by the movement of the tongue.

55

33. In a child's sulky, a main frame, supports to prevent the vehicle from tilting too far forwardly and backwardly, wheel supports, a tongue pivotally connected with the vehicle, operative connections between the 60 tongue and the first-named supports and the wheel supports for simultaneously folding and unfolding the first-named supports and the wheel supports, and means for locking the forwardly-extended end of the 65 tongue in vertically adjusted position.

34. In a collapsible child's vehicle, a main frame, a tongue pivoted on the main frame, a spring latch, and means for engagement with the latch to support the outer end of 70 the tongue at various elevations, combined with foldable wheel supports, and a foldable support pivoted to said frame to prevent the vehicle from tilting too far, and connections between the tongue and said 75 foldable members to fold and unfold the same simultaneously.

35. In a child's sulky, a main frame, foldable wheel supports, a foldable support which prevents the vehicle from tilting too far, a 80 tongue, a locking means carried by said frame, and means carried by said tongue and by said support adapted to coöperate with said locking means to automatically lock all of said foldable members in either 85 folded or unfolded relation.

36. In a child's sulky, a main frame, foldable wheel supports, a foldable support which prevents the vehicle from tilting too far, a tongue, a locking means carried by 90 said frame, and means carried by said tongue adapted to coöperate with said locking means to adjust the tongue in various adjusted positions and to lock all of said members in unfolded operative position.
